UNITED STATES PATENT OFFICE.

THOMAS L. SMITH, OF MILWAUKEE, WISCONSIN.

ROCK-CRUSHER.

1,050,398.

Specification of Letters Patent. Patented Jan. 14, 1913.

Application filed October 29, 1910. Serial No. 589,778.

To all whom it may concern:

Be it known that I, THOMAS L. SMITH, a citizen of the United States, residing in Milwaukee, in the county of Milwaukee and 5 State of Wisconsin, have invented a new and useful Rock-Crusher, of which the following is a specification.

My invention relates to improvements in rock crushers of the gyratory type; and the 10 objects of my invention are to provide a compact machine in which the oscillating or gyrating means for the crusher head is inside of said head, but in which the head is given a movement of different amplitude at 15 the top from that given at the bottom thereof, to make the machine dust-proof as to its wearing surfaces and to provide a circulating oiling means for the gyrating and the driving means and an efficient head adjusting device. I attain these objects by the mechanism 20 illustrated in the accompanying drawing and subsequently specified in the claims.

Figure 1 of the drawing shows a central vertical section, through the crusher and 25 Figs. 2 and 3 show details.

A is the frame of the crusher which is provided with a strong spider a at its lowest part. This frame also carries the concaves a' and is provided with flanges a'' for 30 positioning the machine on the foundation sills B.

C is the crown piece rigidly bolted to the frame A. The crusher shaft D is stationary and rigidly supported in the spider a and 35 crown piece C. The center line of the shaft D and of the crusher frame is d d' .

The crusher head E is vertically adjustable on a sleeve F which is termed a head liner, and both crusher head and head liner 40 are given a gyratory or oscillating movement by an eccentric sleeve G which is rotated on the stationary shaft D as an axis by means of the bevel gear g and bevel pinion g' . The bore of the eccentric sleeve G 45 has the center line d d' , whereas the outside of the eccentric is turned on the center line d d' which makes an angle with the line d d' , both lines intersecting in the point d . As the lower end of the eccentric has more 50 eccentricity than its upper end, and as, if the eccentric were continued to the point d , its eccentricity would become *nil*, any point in the head liner or crushing head, when held from turning while the eccentric is being 55 rotated, will move in the surface of a sphere which has the point d for a center and the

distance from d to the point in question for a radius. Thus, any point in the flange f at the bottom of the head liner will have a wabbling movement in a spherical surface 60 having d f' for a radius and a point in the collar f^2 at the upper end of the head liner will have a movement in the surface of a sphere having d c' for a radius. The flange f and the plate a^3 which covers the well for the 65 gears g and g' , are therefore made with a partial spherical bearing between them. Likewise the collar f^2 at the upper end of the head liner F and the lower surface of the hub of the crown piece C are made 70 with a partial spherical bearing. The collar f^2 and the flange f are spaced apart by the distance collar e , the crusher head E and the adjusting jack screws e' which latter should be so adjusted that a little oil will work out 75 of these spherical bearings.

H is an oil reservoir, from which the oil is taken by the rotary or other form of pump h and delivered through the pipe h' to the top of the eccentric G. From thence it 80 gravitates inside and outside of the eccentric sleeve to the well in which the gears are placed and back to the reservoir through the pipe h^2 . As all the spaces between all live bearing surfaces in the crusher form part of 85 or are connected with this oil channel, all the working surfaces are lubricated.

In order to avoid the possibility of the shaft D sticking fast in the crown piece C, the upper end of the shaft is made tapered at d^3 90 and a taper thimble w made in halves is forced into the annular space between d^3 and the crown piece by means of a stud bolt in the shaft and a nut and washer. The same stud bolt engages the cap p to hold the 95 same in place.

After the distance between the curved flanges f and f^2 has been properly adjusted by means of the jack screw e' , this screw is retained in its adjusted position by the 100 set screw s which is tapped in the collar g which collar has one of its sides conformed to the curve of the head liner F.

What I claim is:

1. A rock crusher comprising a frame supporting an annular crushing member, a stationary shaft firmly supported at both ends in the frame, a movable crusher head surrounding said shaft, an eccentric sleeve on said shaft and in said head, having greater 105 eccentricity at its lower than at its upper end and spherical bearings between the ends 110

of said head and the adjacent parts of said frame.

2. A rock crusher comprising one movable and one annular stationary crushing member, a stationary shaft through the annular member supported at each end in the frame, an eccentric sleeve in the movable crusher member and on said stationary shaft, said sleeve being formed with the center lines of its inside and outside surfaces intersecting, said sleeve carrying a part having a spherical bearing against the frame at each end, said bearings having the center line intersection for a center.

3. A rock crusher comprising an annular crusher member and a movable crusher head therein, a stationary shaft, a rotatable eccentric sleeve on said shaft, having greater eccentricity at one end than the other, a sleeve in the crusher head and fitting said eccentric having a partial spherical bearing with a part of the frame.

4. In a rock crusher, the combination of a frame having a crown piece and a spider, a stationary shaft connecting the same, a concave crusher member in the frame and a gyrating crusher head around said shaft, an eccentric sleeve within said head and on said shaft, spherical bearing surfaces on said spider and said crown piece, and corresponding spherical surfaces connected with said gyrating head and bearing against said crown and spider.

5. In a rock crusher, a frame and spider, a removable crown piece, a stationary shaft connecting the same, an eccentric sleeve on said shaft, a crusher head around said sleeve, the center lines of the shaft and of the ec-

centric intersecting in a point above the crusher, spherical bearings on said spider and crown piece and corresponding bearings on said head, both bearings having said intersection for a center, and means for adjusting the bearings on the head to bear against those on the crown piece and spider.

6. In a rock crusher, a frame and spider, a removable crown piece, a stationary shaft connecting the same, an eccentric sleeve on said shaft having its center line and that of the shaft intersecting in a point above the crusher, a crusher head around said eccentric, spherical bearings on said crown piece and spider having said intersection for a center, a sleeve fitting within the head and on said eccentric, a spherical bearing on the end of said sleeve bearing against said spider, a collar carried by the upper end of said head having a spherical bearing to fit against said spider, and means for adjusting said head and collar relatively to said sleeve and its bearing against the spider.

7. In a rock crusher, an annular frame having an integral spider at the bottom and a removable crown piece at the top, a stationary shaft secured in a central bearing in the spider, the upper end of said shaft in the crown piece being tapered, a split collar tapered on the inside to fit the shaft, and cylindrical on the outside to fit the crown piece and means for clamping the taper collar in place.

THOMAS L. SMITH.
